HARLEY A. W. HOWCOTT, OF BATON ROUGE, LOUISIANA

PUMPING APPARATUS

Application filed March 26, 1928. Serial No. 264,726.

This invention appertains to improvements in pumping apparatus generally, and more particularly to types of such apparatus usually employed in pumping fluids from deep wells, such as oil wells and the like.

An object of the invention is to provide for an apparatus of the class set forth, which is of a comparatively simple and inexpensive, but durable and efficient construction and arrangement of parts, and which will effectively facilitate the pumping operations from deep wells with a minimum of extraneous power applied to the apparatus for the purpose.

Another object of the invention is to provide for an apparatus or device as hereinbefore characterized, which embodies a movable weight mechanism mounted and arranged for effecting the actual pumping operations alone, or for cooperation with a prime mover of a minimum horse power for accomplishing such operations in the efficient manner as aforesaid.

A further object of the invention is to provide for a pumping apparatus or mechanism of the character mentioned, which will be capable of effectively and efficiently pumping fluids from more than one well at one and the same time, and which embodies means for counter-balancing certain of the operative parts thereof when a pumping operation is being carried out at one well only.

With the foregoing and other equally important objects and advantages in view, the invention resides in the certain new and useful combinations, constructions and arrangements of parts and mechanisms as will be hereinafter more fully described, set forth in the appended claims, and illustrated in the accompanying drawings, in which:

Figure 1 is a front elevation of a practical embodiment of one form of the invention,

Figure 2 is a side or end elevation of the same,

Figure 3 is a fragmentary top plan view thereof,

Figure 4 is an enlarged sectional detail through the upper end of a supporting standard, and showing the mode of mounting the upper sprocket thereon,

Figure 5 is a perspective view of one of the operative parts or pitmen of the power transmitting mechanism of the apparatus,

Figure 6 is a fragmentary front elevation of a second or modified form of the apparatus, and

Figure 7 is a vertical transverse section taken on the line 7—7 of Figure 6.

Referring to the drawings, wherein like characters of reference designate corresponding parts throughout the several views thereof, and more particularly to Figures 1 to 5 inclusive, the embodiment of the invention, as shown therein by way of example, is constituted in a main supporting frame consisting of three equi-distantly spaced and vertically disposed standards 10, 11 and 12, which are connected together at their lower and upper ends by means of horizontally disposed members or bars 13.

Mounted on a suitable supporting base 14 at one side of the intermediate vertical frame member or standard 11 is a prime mover 15, which may be any desired type of power generator, such as the internal combustion engine as shown. The power transmitting shaft 16, of this prime mover 15, is journaled through the standard 11, and has a gear element 17 keyed on its free end at the opposite side of the latter.

Arranged above and in mesh with the gear element 17 is a second gear element 18, which is keyed or otherwise secured on the free end of a shaft 19 journaled in a suitable support 20. Secured on the outer face of the gear element 18, for rotation therewith, is a sprocket 21, which is connected by a sprocket chain 22 to a second sprocket 23 keyed on the one end of a shaft 24 journaled in the upper end of a standard 25 rising from the support 20. To afford substantial bearing support to the upper sprocket 23, an outwardly bossed bearing plate 26 is positioned between the hub portion of the sprocket and the opposed face of the standard 25, and a flat bearing plate 27 is similarly positioned between the opposite face of the standard 25 and a bearing collar 28 keyed on the end of the shaft 24 opposite to that end on which the sprocket 23 is

secured. These bearing plates 26 and 27 are secured to the standard 25 by means of bolts or the like 29.

Eccentrically secured to a common pivot 30 projecting outwardly of the front face of the upper sprocket 23, are a pair of oppositely directed pitmen 31, which have their outer ends separately pivoted, as at 32, to a horizontally disposed connecting member 10 or bar 33. Secured on the front face of this connecting member or bar 33, and at the center thereof, is a pivot member 34, which is engaged by the upper end of a pendulum arm or rod 35. This member or rod 35 is mounted for oscillating or swinging movements on a pivot member or pin 36 projecting outwardly from a supporting plate 37 secured at the front side of the intermediate vertical frame member or standard 11. The lower and longer end portion of this member or rod 35 is preferably screwthreaded for a distance upwardly of its extreme free end to receive a follower or nut 38 thereon, upon which a weight 39 is adjustably supported.

The opposite ends of the connecting member or bar 33, beyond the pivot connection 32 of the pitmen 31 therewith, are, in turn, pivotally connected, as at 40, to the vertically directed arms of a pair of bell crank levers or the like 41, which are likewise pivoted, as at 42, at their angled connected portions, one to the front face of the upper end portions of the vertical frame members or standards 10 and 12.

In the use of the apparatus or device, as thus provided, one or both of the bell crank levers 41 are to have their lower and outwardly directed arm portions each pivotally connected, as at 43, to the upper end of a pump rod extension 44, which, in turn, will have its lower end pivoted, as at 45, directly to the upper end of a pump rod 46. The pump rod 46 is, however, and preferably so, passed upwardly from the pump or well casing 47, and through guide members or eyes 48 secured to the outer side face of the standard. When one pump 47 only is to be operatively coupled to a rocker arm or bell crank lever 41, as shown in Figure 1, a rod 49 will be attached to the pivot connection 43 of the lower arm of the other of the rocker arms or bell crank levers to suspend an adjustable weight 50 therefrom to counterweight or balance the weight of the load of the pump rod 46 and other movable parts (not shown) of the usual pump equipment, connected to the rocker arm or lever at the opposite side of the frame. This weight 50 is preferably engaged on the lower end portion of the rod 49 for vertical sliding adjustments thereon, and is supported in any desired position of adjustment on a follower or nut 51 threaded on the extreme lower end 65 of the rod for the purpose.

In the operation of this form of the apparatus or device, and with the same installed in position at one side of a well, and the rocker arm or bell crank lever 41, at the near side thereof, operatively connected through the extension rod 44 to the pump rod 46 of the pump 47, the prime mover 15 will be started up, when power from the same will be transmitted through the intermeshed reducing gears 17 and 18, and from the gear 18 by way of the sprocket 21 rotatable therewith and the chain 22 to the upper sprocket 23. Assuming the power applied to the sprocket 23 to rotate the same in a clockwise direction, and with the parts of the mechanism initially positioned as shown, the pitmen 31 will impart a reciprocating movement to the connecting member or rod 33, which will, in turn, impart a rocking movement to the bell crank levers 41 on their fixed pivots 42, and, as a consequence whereof, a rectilinear motion will be imparted to the pump rod 46. With the initial reciprocating movement of the connecting member or rod 33, an oscillating movement will be imparted to the pendulum rod 35, which, under the impetus of the weight 39 will relieve the prime mover of a major portion of the working load. The effectiveness of the working stroke of the pendulum rod 35 may be regulated to a nicety by adjusting the weight 39 on the lower end portion thereof, which may be readily accomplished by applying a wrench to the follower or nut 38. As has been hereinbefore suggested, a second pump may be coupled to the bell crank lever 41 at the opposite side of the frame, in which case, the counter-balancing weight 50 will be removed for the purpose.

Referring now to Figures 6 and 7, the modified form of the apparatus shown therein contemplates the substitution of a simple form of weight motor for the prime mover 15 and its associated power transmission mechanism as constituted in the reducing gears 17 and 18, and the lower and upper sprockets 21 and 23 and the chain 22 connecting the latter.

In this instance of the invention, a gear element 152 will be secured on a shaft 153, which will be journalled in the upper end portion of the standard 125 rising from the base 120. This gear element 152 will be located in the approximate position of the upper sprocket 23 of the first form of the device, and will have an eccentric connection 130 projecting from its front face to receive thereon the adjacent ends of the oppositely arranged pitmen 131, which are pivotally connected at their other ends, as at 132, to the connecting member or rod 133. Similarly, the opposite ends of the connecting member or rod 133 will each be pivotally connected, as at 140, to a rocking arm or bell

crank lever 141, which is pivoted, as at 142, at its center to the upright frame member 111 of the main frame of the apparatus. The free end of the other or lower arm of the rocking member or bell crank 141 will be pivotally connected, as at 145, to the pump rod extension 144, which is pivoted to the upper end of the pump rod, as in the first instance.

- 10 Rising from the base 120 in spaced relation to and in rear of the standard or upright 125 is a second standard or upright 154, and journaled in the extreme upper ends of both standards or uprights in a shaft 155 on the intermediate portion of which is a drum 156. The front end of the shaft 155 is projected forwardly of the front standard 125, and is similarly journaled in the upper end of a standard or upright 157 arising from the upper end of the central or intermediate standard or upright 111 of the main frame. Keyed on the shaft 155 between the standard or upright 157 and the upper end portion of the standard 125 is a smaller gear element 158 which is meshed with the gear element 152. The foregoing apparatus constitutes the main power means or prime mover of this modified form of the invention, and the same is to be supplemented with a secondary power means as follows: Mounted on the rear end of the shaft 155 beyond the rear face of the standard 154 is a gear element 159, which is meshed by a smaller gear element 160 keyed on the shaft of a secondary power device or electric motor 161. This power device or motor 161 is supported from the standard 154 on a bracket 162. Normally wound on the drum 156 is a flexible cable or the like 163, which has one end fastened thereto and its other end free to be attached to a weight 164. As shown, the base 120 is preferably formed to provide an open hollow center so that the weight 164 will have an added travel downward within the same and thereby correspondingly increase the time period of operating of the mechanism actuated by the unwinding of the cable 163 under the action of the descending weight.

15 In the operation of this form of the apparatus or device, and with the cable 163 wound upon the drum 156 and a pump rod connected to the extension 144 depending from a rocker arm or bell crank lever 141, at one side of the main frame, upon the release of the drum 156 for free rotation with its supporting shaft 155, the weight will descend between the standards or uprights 125 and 154 and the cable 163 will unwind from the drum and rotate the same. The power derived from the rotation of the drum 156 will now be transmitted to the reducing gears 156 and 152 and from the gear 152 to the pitmen 131, when the latter will reciprocate the connecting bar 133. Upon the

initial reciprocation of the connecting bar 133, the weighted pendulum bar 135 will be oscillated on its pivot 136 by reason of the pivot connection 134 at its upper end to the connecting bar 133. Thus the combined power from the drum 156 and the pendulum 135 will be transmitted by the connecting bar 133 to the rocking arm or bell crank lever 141 and the pump rod connection 144. When the weight 164 has reached the extreme limit of its downward travel at the bottom of the hollow center of the base 120, the apparatus will stop, and the power device or motor 161 will thus be started up and through the medium of the meshing gears 160 and 159 will rewind the cable 163 onto the drum 156 for a subsequent or repeat operation of the pumping operation.

20 It is to be noted that in both forms of the invention, suitable brace members 25', on the one hand, and 125' and 154', on the other hand, will be employed in conjunction with the standards or uprights 25, 125 and 154, respectively, substantially as shown.

25 Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

30 Having thus fully described the invention, what is claimed is:

1. In a power device for pumps, a prime mover, a main frame spaced from said prime mover, an auxiliary frame interposed between said prime mover and said main frame, a power transmitting mechanism carried by said main frame and operably connected to said prime mover, and a power equalizing device carried by said auxiliary frame and operatively connected to said power transmitting mechanism.

35 100 165 110
2. In a power device for pumps, a prime mover, a main frame spaced from said prime mover, an auxiliary frame interposed between said prime mover and said main frame, a power transmitting mechanism carried by said main frame and operably connected to said prime mover, and pendulum actuating mechanism carried by said auxiliary frame and operably connected to said power transmission mechanism for equalizing the power from said prime mover.

40 115 120 125 130
3. In a power device for pumps, a main frame, a weight motor carried by said frame, an auxiliary frame disposed at one side of said main frame, means carried by said auxiliary frame for transmitting power from said weight motor to a pump, mechanical means cooperable with said power transmission means for equalizing the power delivered therefrom to said pump, and a power

operated means carried by said main frame for restoring the power of said weight motor after each of its operations to exhaustion.

5. 4. In a power device for pumps, a main frame, a weight motor carried by said frame, an auxiliary frame disposed at one side of said main frame, means carried by said auxiliary frame for transmitting power from 10 said weight motor to a pump, pendulum means cooperable with said power transmission means for equalizing the power delivered therefrom to said pump, and a power means carried by said main frame for restoring the power of said weight motor after each 15 of its operations to exhaustion.

5. In a power device for pumps, a main frame, a weight motor carried by said frame, an auxiliary frame disposed at one side of 20 said main frame, means carried by said auxiliary frame for transmitting power from said weight motor to a pump, mechanical means cooperable with said power transmission means for equalizing the power delivered 25 therefrom to said pump, and a power means carried by said main frame for restoring the power of said weight motor after each 30 of its operations to exhaustion, said mechanical means also cooperating with said power operated means during its periods of operation to restore the power of said weight motor.

6. In a power device for pumps, a prime mover of minimum power capacity, rotary 35 means for transmitting power from said prime mover, means for translating the rotary motion of said transmitting means into reciprocatory motion at a pump, and a pendulum means cooperative with said power translating means for equalizing the power delivered thereby to the pump.

7. In a power device for pumps, a prime mover, a frame supporting said prime mover, means carried by said frame for 45 transmitting power from the prime mover to a pump, means for equalizing the power delivered to the pump from said transmitting means, and means for restoring the power of the prime mover after each 50 operative movement thereof to exhaustion.

8. In a power device for pumps, a prime mover, a frame supporting said prime mover, means carried by said frame for transmitting power from the prime mover to a 55 pump, means for equalizing the power delivered to the pump from said transmitting means, and power operated means for automatically restoring the power of the prime mover after each operative movement 60 thereof to exhaustion.

9. In a power device for pumps, a frame, power means carried by said frame, means transmitting power from the power means to a pump, means for equalizing the power 65 delivered to the pump from said transmit-

ting means, and a second power means for automatically restoring the power of said first named power means after each operative movement thereof to exhaustion, said power equalizing means also acting to 70 equalize the power of said second power means during its periods of restoration of power to the first named power means.

10. In a power device for pumps, a prime mover, a frame supporting said prime mover, means carried by said frame for transmitting power from the prime mover to a pump, mechanical means for equalizing the power delivered to the pump from said transmitting means, and means for automatically restoring the power of the prime mover after each operative movement 75 thereof to exhaustion.

11. In a power device for pumps, a prime mover, a frame supporting said prime mover, means carried by said frame for transmitting power from the prime mover to a pump, weighted mechanical means for equalizing the power delivered to the pump from said transmitting means, and means for automatically restoring the power of the prime mover after each operative movement 80 thereof to exhaustion.

12. In a power device for pumps, a prime mover, a frame supporting said prime mover, means carried by said frame for transmitting power from the prime mover to a pump, a pendulum means for equalizing the power delivered to the pump from said transmitting means, and means for automatically restoring the power of the prime mover after each operative movement 95 thereof to exhaustion.

13. In a power device for pumps, a prime mover, a frame, means carried by said frame for transmitting power from the prime mover to a pump, mechanical means for equalizing the power delivered to the pump from said transmitting means, and power means for automatically restoring the power 105 of the prime mover after each operative movement thereof to exhaustion, said power equalizing means also acting to equalize the power of said power means during its periods of restoration of power to the prime 110 mover.

14. In a power device for pumps, a prime mover, a frame, means carried by said frame for transmitting power from the prime mover to a pump, weighted mechanical 120 means for equalizing the power delivered to the pump from said transmitting means, and power means for restoring the power of the prime mover after each operative movement thereof to exhaustion, said power equalizing means also acting to equalize the power of said power means during its periods of restoration of power to the prime 125 mover.

15. In a power device for pumps, a prime 130

mover, a frame, means carried by said frame for transmitting power from the prime mover to a pump, a pendulum means for equalizing the power delivered to the 5 pump from said transmitting means, and power means for automatically restoring the power of the prime mover after each operative movement thereof to exhaustion, said power equalizing means also acting to 10 equalize the power of said power means during its periods of restoration of power to the prime mover.
